Seance Pirot of Hackahan N.J.

Assign to

Rubber Clothing Co. of N.Y.

Letter Patent No. 2483. Dated Oct. 2, 1864.

Design for a Child's Long Comb.

The Schedule referred to in the Letters Patent and making part of the same

To all whom it may concern:

Be it known that I, Seance Pirot of Hackahan in the County of Hudson and State of New Jersey, have invented or produced a New and Original Design for ornamenting combs, and I hereby declare the following to be a full, clear and exact description of the same, reference being had to the accompanying drawing which represent on elevation and a top view of a comb to which my design has been applied.

The Design invented by me consists in a row or string of beads arranged around the top, of what is known to the trade, as a child's long comb, in a line parallel to its upper edge. The beads which may be of any desired color, are secured by being strung on a wire supported by metal loops which are inserted and riveted in hold drilled in the comb at suitable distances apart. Other beads however may be secured to the comb in various other ways which need not be mentioned, as the method of holding the two together, forms no part of what I claim.

In testimony whereof, I have signed my name to this Specification before two subscribing witnesses.
